Application February 17, 1948, Serial No. 8,815

9 Claims. (Cl. 113—42)

1

The present invention relates to the class of machines generally known as power presses which are commonly used for practically all operations which may be performed on work passed through the machine, such as for example blanking, drawing, stamping, embossing, die forming, plastic moulding, extrusion, etc. More particularly, this invention relates to such presses of the double action type and with "underdrive," where the drive-shaft is located in the base of the machine.

The principal object of the invention is the provision of a novel power press with underdrive having coactive rams or slides for combined blanking and drawing operations, said slides being actuated in timed relation one to the other during the operation of the machine. The upper ram or drawing slide is preferably connected to a lower cross-head by means of draw-rods and reciprocated by a drive-shaft of the crank or eccentric type, while the coactive lower ram or blanking slide may be connected to another lower cross-head by means of other draw-rods. The blanking slide is preferably reciprocated from the same drive-shaft as the drawing slide, either by a crank mechanism or by suitable cams, depending on the desired motion of said blanking slide and the timed relationship between said blanking slide and said drawing slide.

Another object is to provide adjustable means for maintaining the alignment between blanking slide and drawing slide.

A still other object of the invention is to provide an auxiliary ram movement, in addition to the reciprocating blanking and drawing slides, by so locating the lower cross-head which is connected to the blanking slide that it is available for such simultaneous auxiliary operations as embossing, calibrating, flattening the bottoms of drawn cups, or as a positive knockout or ejector.

Another object is to provide hollow draw-rods for connecting the blanking slide to its lower cross-head, the other draw-rod which connects the drawing slide to its respective cross-head, being slidingly guided inside said hollow draw-rods.

A further object is to provide the draw-rods for the drawing slide and/or the draw-rods for the blanking slide with wear resisting sliding surfaces.

These and other definite further objects of the invention will appear as the mechanism is described in detail. In the accompanying drawings I have shown certain characteristic embodiments of the invention, in which

2

Fig. 1 shows a blanking and drawing press embodying the invention with the lower part of the press in cross-section along line 1—1, Fig. 2;

Fig. 2 is a right hand side view of the press depicted in Fig. 1;

Fig. 3 illustrates in somewhat diagrammatic form a single blanking and drawing die for making cups to demonstrate one particular type of work for which the press is intended;

Fig. 4 is a cross-section along line 4—4 of Fig. 5 and shows a modification of the press shown in Fig. 1 with a crank actuated blanking slide and with blanking slide and drawing slides slidably guided on the frame of the press;

Fig. 5 depicts a cross section along line 5—5 of Fig. 4;

Fig. 6 shows an auxiliary tool mounted on the blanking cross-head.

Referring to Figs. 1 and 2 of the drawings, the machine comprises a main frame 11 which may be placed directly on a floor. A heavy cross-rib 12 of frame 11 forms the press table on which the blanking die is usually supported. The drawing punch is adapted to be carried by a generally square or rectangularly shaped upper ram or drawing slide 13, which is located above table or die-support 12 and operatively connected to a similarly shaped lower cross-head 14 by four cylindrical rods 15, which are shown to be of solid cross-section, but which may also be made of tubular cross-section to decrease their mass. The opposite ends of the rods 15 may be tied to the upper drawing slide 13 and lower cross-head 14 by means of nuts 16 and lock-nuts 17.

The blanking punch may be carried by lower ram or blanking slide 18, which is located between drawing slide 13 and press bed 12 and operatively connected to a lower cross-head 19 by four hollow, cylindrical rods 20 whose opposite ends may be tied to the blanking slide 18 and lower cross-head 19 by means of nuts 21. To differentiate between the lower cross-heads, cross-head 14 will be called "drawing cross-head" and cross-head 19 "blanking cross-head." The blanking and drawing slides as well as the blanking and drawing cross-heads may also be referred to generally as "cross-head elements." The draw-rods 15 are slidingly guided inside the hollow draw-rods 20.

Drawing slide 13, draw-rods 15, and drawing cross-head 14 form one frame structure which will be identified as drawing frame A. Blanking slide 18, tubular rods 20, and blanking cross-head 19 form another frame structure which may be called blanking frame B.

A crankshaft or eccentric shaft 22 is located between drawing cross-head 14 and blanking cross-head 19. For convenience in assembly, the frame 11 may be divided in a lower base 11b and a top 11a. Bolts 23 connect these two halves rigidly, and if good and sufficient reasons do not require the identification of one particular half of the frame, it will be simply referred to as frame or main frame 11. Crankshaft or drive-shaft 22 is journaled in main bearings 24 and 25 in frame 11 and carries a pitman 26 connected to drawing cross-head 14 by a suitable connection for reciprocating the drawing frame A, such as a left and right hand screw 27 between pitman 26, and pin-type connection 28. This and similar adjustable pitman connections are common to machines of this general type and are useful in setting the dies.

Drive-shaft 22 carries also two identical, constant-diameter cams 29 for actuating the blanking frame B. The cam 29 rides between upper roller follower 30 and lower roller follower 31, one of which may be mounted on an eccentric pin (not shown) to take up any wear or lost motion. The upper ends of rods 33 of the cam yoke 32 are threaded into tapped holes of blanking cross-head 19. Rollers 30 and 31 are rotatably mounted in upper and lower cross-members 34 and 35, respectively, which form a substantial and rigid structure in combination with rods 33 for positive control of the blanking slide 18 on both the upward and downward strokes. The cam yokes 32 are guided in drawing cross-head 14 by rods 36, fast to cam yokes 32 and resting on springs 37 for damping purposes.

It will be understood that the shape of the cams 29 may be changed to suit requirements. As a matter of fact, the main reason for choosing a cam drive for the blanking frame B is to be found in the variety and combinations of motions obtainable with such means. The shape of the cams shown, for instance, controls the blanking slide 18 in such a way that a blanking operation may be performed before the dwell begins at the bottom position of the blanking frame B, which may be advantageously utilized for holding the blank until the draw has been started as will appear later. The blanking frame B and the drawing frame A may be actuated by the cam and crank mechanisms, respectively, in any desired timed relationship to adapt the press to different sequences of operations.

Drive-shaft 22 carries a clutch flywheel 38 and a suitable brake 39 for bringing the press to a stop. The press may be driven in any ordinary manner, such as by an electric motor and belt drive (not shown) on clutch flywheel 38. The latter may be coupled with crankshaft 22 in any suitable manner and not specifically shown herein, because these clutching means will be readily understood by those skilled in the art and are not necessary for a clear understanding of the invention.

Figs. 1 and 2 show the drawing frame A guided by means of draw-rods 15. These rods 15 are nested inside of hollow rods 20 and may be slidably guided thereon, as previously described. In addition, rods 15 are slidably guided in bushings 40 held in pads 41 of frame 11. The blanking frame B is similarly guided in cylindrical bushings 42 held in press bed 12. Indirectly, but effectively, the blanking frame B is further maintained in alignment because of the guiding action experienced by rods 15 in bushings 40. The extreme accuracy which is expected of certain

work contemplated on this type of press presupposes extremely precise guiding of the blanking and drawing slides and their perfect alignment with each other and with the press bed 12.

Because of the new principle of using hollow draw-rods for actuating one press slide and for guiding the draw-rods of a second coactive slide inside these hollow draw-rods, an extraordinarily dependable twin guiding method has been created; i. e. the hollow rods 20 are guided in long cylindrical bushings 42, which for all practical purposes form part of the rigid main frame 11; in addition, the hollow rods 20 are in turn held in alignment by the solid rods 15, which may be guided along substantially the entire length of the hollow rods 20 and also in the long cylindrical bushings 40, which for all practical purposes also form part of the rigid main frame 11.

In addition, the nesting of draw-rods 15 inside the tubular connecting means or nesting means 20 permits a symmetrical, four point suspension of the slides 13 and 18 on their respective peripheries, preferably near their corners as shown, whereby the elastic deformations or deflections of these highly loaded members 13 and 18 are kept to a minimum without sacrificing accessibility to the tools and dies mounted on the slides and press bed. The slides 13 and 18, as well as their associated cross-heads 14 and 19 are therefore supported along their respective peripheries at intervals of less than 180 degrees, considering the geometrical center of any one of these slides or cross-heads as the center of an imaginary reference circle normal to the longitudinal axes of rods 15 and tubular or nesting means 20, respectively.

While cylindrical bushings have been shown at 40 and 42, adjustable split tapered bushings as shown in Fig. 4 (42'), may be used instead.

To insure continuous high speed operation without undue wear of the sliding surfaces of rods 15 and 20, provisions for ample lubrication should be made and the construction materials selected for these rods should possess appropriate properties, for instance, with respect to relative hardness. Thus a somewhat softer material may be used for the outside draw-rods 20 than the inner rods 15; or the sliding surfaces of the rods may be coated mechanically or electrically with suitable bearing materials; or one of the contacting sliding surfaces may be chromium plated; or an actual bushing or bushings may be interposed between the telescopic rods; or a combination of these methods may be employed.

A substantial spring 43 is placed between drawing cross-head 14 and the bottom of frame 11 for the purpose of counterbalancing the weight of the drawing frame A. The frame 11 may be provided with a plurality of openings or windows as at 44 to permit access to the operating mechanism.

Figs. 4 and 5 show a similar double acting blanking and drawing press. Similar parts have received identical numerals with a prime mark added, thereby simplifying the description.

The frame 11' is shown extended beyond the press table 12' for further supporting and guiding of drawing slide 13' and blanking slide 18'. The latter is guided on main frame 11' by means of long, adjustable V-type gibs. Slide 18' may be provided with corresponding V-shaped grooves 46 adjacent to the corners thereof. Matching gibs 45 may be held against side movement between suitable vertical shoulders 47 of frame 11'. A plurality of set-screws 48, threaded in tapped

holes of frame 11', abut the vertical gibs 45 for adjustment of the sliding clearance between the gibs 45 and blanking slide 18'. Lock-nuts 49 serve the purpose of maintaining set-screws 48 in their adjusted positions. Bolts 50, threaded into tapped holes of gibs 45, are adapted to draw the gibs up against set-screws 48. The gibs 45 rest at their lower ends on shoulders 51 of the main frame 11'. The drawing slide 13' and the drawing cross-head 14' are guided in similar fashion on the main frame 11', and if required, the blanking cross-head 19' may also be further guided on the frame 11' as shown and described for slides 13', 18', and drawing cross-head 14', but the necessity for this will depend on the severity of the auxiliary operation which this blanking cross-head 19' is called upon to perform.

Instead of in plain cylindrical bushings, the hollow rods 20' are shown guided in the press bed 12' by means of split tapered bushings 42', threaded at their upper ends and adjustable by means of coating threaded nuts 75 which rest on top of bed 12'.

The blanking frame B is shown reciprocated by a crank mechanism, similar to that for reciprocating the drawing frame A. The common drive-shaft 22' carries on spaced apart crank pins two pitmans 52 and 53 to the left and right, respectively, of pitman 26'. These pitmans 52 and 53 are connected to blanking crosshead 19' by suitable connections for reciprocating the blanking frame B, such as left and right hand screws 54 and 55 between pitmans 52, 53 and pin-type connections 56 and 57, respectively. Thus, the movements of blanking as well as drawing frames are controlled by crank mechanisms. While fixed stroke lengths have been shown for both crank mechanisms, these crank mechanisms may be provided with angularly shiftable eccentric means for changing their respective strokes as taught in my copending application Serial No. 8814, series of 1948, for an opposed reciprocating slide press, whereby the range of application and utility may be considerably extended. The crankshaft may also carry angularly adjustable rotatable counterweights which are also illustrated and described in said copending application.

This type of press is specially suitable for the mass production of drawn articles such as primer caps, shallow boxes, covers, eyelets, bottle caps, etc. with single or multiple dies. While the press may be advantageously employed for many other types of punch press work and while individually fed blanks or slugs may be operated on, I have arbitrarily elected to describe the action of the press for the sake of explanation and illustration in connection with the blanking and drawing of cups from strip material. Strip or coil material is generally fed through the dies by means of automatic feeds, such as roll feeds, indicated diagrammatically in Fig. 1 at 58 and 59. Such roll feeds are well known in the art and are usually operated by an adjustable crank disc 60 fastened to the crankshaft. A cam drive or a Scotch yoke quick-return motion may also be used when the angle through which the feeding can take place is small. The coiled stock or strip is fed in synchronism with the reciprocating movement of the press by intermittently driven rolls.

The location of the tools or dies is indicated in Fig. 1. Fig. 3 shows these tools for convenience to a larger scale. The combined blanking and drawing die 61 is fastened to die-shoe 62 mounted

on the press bed 12. The cutting edge is at 63; the drawing radius at 64. The work material or strip 65 is fed slightly above the blanking and drawing die 61. Blanking punch 66 with spring loaded stripper 67 are mounted in die-shoe 68 fast to blanking slide 18. Blanking punch 66 has a concentric bore 69 to let drawing punch 70 pass therethrough. Drawing punch 70 is mounted in die-shoe 71, suitably fastened to drawing slide 13. The mounting of the die-shoes may be effected in a number of different ways, bolts passing through or being threaded into tapped holes of the slides being common.

When the feeding cycle has been finished and the strip 65 is at rest, the spring loaded stripper 67 of the descending blanking slide 18 will hold the strip against the upper surface of blanking die 61. As the blanking slide 18 descends further, the blanking punch 66 will penetrate the strip and separate the blank 72 from the strip 65. This blank will drop into the position shown in Fig. 3 and rest on top of the drawing part of the die. The cams 29 will cause the blanking slide 18 to descend still further, until, at the bottom dead-center position of slide 18, the lower surface of the blanking punch 66 engages the blank 72 and will act as blank holder during part of the drawing process. The usefulness of the dwell imparted by the cams 29 to the blanking slide in lowest position will now be appreciated. Meanwhile, the drawing slide 13 with drawing punch 70 has also descended and starts pushing the blank 72 over the drawing radius 64 and through the cylindrical part 73 of the drawing die, which is of substantially the same diameter as the desired outside diameter of the finished cup 74. The latter expands sufficiently after having passed the lower edge of the cylindrical portion 73 to be stripped off the ascending drawing punch 70.

The advantages of this method consist primarily in the simplicity of the punches and dies required and in the fact that the blanking and drawing operations are accomplished in one stroke of the press. If the rounded bottom of the finished cup 74 is desired to be flat, a suitable punch may be mounted on blanking cross-head 19 to perform this auxiliary operation. Embossing of the bottoms of cups may be effected in an analogous manner. In some types of drawing work, it is not desirable to use the "push-through" method of drawing described above. It may be preferable to eject the finished article upwards through the drawing die. For this purpose, the blanking cross-head 19 may supply the movement for a positive ejector or auxiliary tool such as indicated for example at 76 in Fig. 6. Still other punch press operations may require in addition to the movements provided in the press the use of air cushions, rubber or spring pads.

It is obvious that the machine may also be employed as a single acting press. Then either the drawing slide 13, or preferably the blanking slide 18 may carry the upper part of the tools, usually the punch, while the lower part of the tools, usually the female die, may be mounted on the press table 12.

Four gibs 45 have been shown for guiding the slides and cross-heads of the machine, but actual requirements may dictate the use of fewer or more gibs. While the gibbing arrangement shown is of the V-type, any other gibbing known in the art, such as square gibbing, flat V-gibbing, etc. may be employed. The novel mutual guiding principle for blanking frame and drawing

frame, employing telescoping draw-rods, may be employed in combination with suitable guiding means for the outside draw-rods, such as bushings 42 or 42' in Figs. 1 and 4; or one or more of the additional guiding means shown or described may be used in addition thereto; or guide bushings 42', Fig. 4, may be eliminated altogether, if at least either the drawing slide 13' or the blanking slide 18' is slidely guided above the press bed 12' on the main frame 11' and if at least one of the cross-heads 14' or 19' or the draw-rods 15' are guided below the press bed 12'.

Instead of actuating one slide by means of cams and the other one by means of a crank mechanism (Figs. 1 and 2), both movements may be produced by suitably arranged cams, just as both movements are produced by means of crank mechanisms in the modification shown in Fig. 4.

Therefore, I do not wish to be limited to the particular constructions shown, which constructions may be varied within the scope of this invention, and it is my intention to cover hereby all adaptations, modifications, and variations thereof which come under the practice of those skilled in the particular art to which the invention relates.

Having thus described my invention, what I claim is:

1. In a press of the character described, a main frame, a drawing slide, a coactive blanking slide, a press bed located below both said slides and forming part of said main frame, a blanking cross-head, located underneath said press bed, tubular means for connecting said blanking cross-head and said blanking slide; a drawing cross-head positioned below said blanking cross-head; cylindrical draw-rods for connecting said drawing cross-head and said drawing slide, said cylindrical draw-rods being guided in said tubular connecting means; common driving means located between said blanking and said drawing cross-heads for reciprocating said blanking slide and said drawing slide in predetermined timed relation to one another, adjustable guiding means associated with said main frame and in sliding engagement with said blanking slide to maintain alignment between said press bed and said blanking slide.

2. A press as described in claim 1, including other adjustable guiding means associated with said main frame and in sliding engagement with said drawing slide.

3. A press as described in claim 1, including adjustable guiding means associated with the press bed to slidely guide said tubular connecting means.

4. In a press, a main frame, a drawing slide, a coactive blanking slide, a press bed located below said slides and forming part of said main frame, a blanking cross-head located underneath said press bed, tubular means for connecting said blanking cross-head and said blanking slide; a drawing cross-head positioned below said blanking cross-head; cylindrical draw-rods for connecting said drawing cross-head and said drawing slide, said cylindrical draw-rods being guided in said tubular connecting means; a common driveshaft located between said blanking and said drawing cross-heads; said drive shaft carrying a constant-diameter cam mechanism for actuating said blanking slide and a crank mechanism for actuating said drawing slide.

5. In a press, a main frame, a drawing slide, a coactive blanking slide, a press bed located below said slides and forming part of said main frame, a blanking cross-head located underneath said press bed, tubular means for connecting said blanking cross-head and said blanking slide; a drawing cross-head positioned below said blanking cross-head, cylindrical draw-rods for connecting said drawing cross-head and said drawing slide, said cylindrical draw-rods being guided in said tubular connecting means; a common drive shaft located between said blanking and said drawing cross-heads; said drive shaft carrying separate crank mechanisms for actuating said blanking slide and said drawing slide in timed relation.

6. In a press with underdrive, a main frame including a press bed; a blanking frame comprising a slide above and a cross-head below said press bed, respectively, and including hollow connecting means between said slide and said cross-head; a drawing frame comprising a second slide above said first-mentioned slide, a second cross-head below said first-mentioned cross-head, and auxiliary connecting means between said second slide and second cross-head; the auxiliary connecting means of said drawing frame being nested and telescopically guided in said hollow connecting means of said blanking frame; and auxiliary guiding means for keeping said blanking frame, said drawing frame, and said press bed in mutual alignment.

7. In a double acting press with underdrive, a main frame having a press bed; a blanking slide above said press bed, a blanking cross-head below said press bed, a hollow connecting means between said blanking slide and said blanking cross-head, a drawing slide above said blanking slide, a drawing cross-head below said blanking cross-head; draw-rods for connecting said drawing slide and said drawing cross-head; said draw-rods being so positioned with respect to said hollow connecting means as to pass therethrough to obtain a high degree of accessibility to said press bed, and a driving mechanism disposed between said blanking cross-head and said drawing cross-head for operating both said slides and their associated cross-heads in timed relation.

8. In a punch press, a drawing slide, a coactive blanking slide, die-supporting means located below both said slides, a blanking cross-head underneath said die-supporting means, tubular means for operably connecting said blanking slide and said blanking cross-head, said tubular means being spaced along the peripheries of said blanking slide and said blanking cross-head for their support at intervals of less than 180 degrees; a drawing cross-head located underneath said blanking cross-head, means for operably connecting said drawing slide and said drawing cross-head; said tubular means being adapted to telescopically guide said connecting means; and common driving means for reciprocating said blanking slide and said drawing slide in timed relation relative to said die-supporting means.

9. In a mechanism of the character described, die-supporting means, a first pair of cross-head elements in spaced apart relation and positioned to one side of said die-supporting means, a second pair of cross-head elements in spaced apart relation and positioned on the other side of said die-supporting means, a plurality of tubular means for connecting one cross-head ele-

ment of said first pair and one cross-head element of said second pair, said tubular means being spaced along the peripheries of said cross-head elements to connect the latter at intervals of less than 180 degrees, auxiliary connecting means for connecting the remaining cross-head element of said first pair to the remaining cross-head element of said second pair, said auxiliary connecting means being so positioned with respect to said tubular connecting means as to nest therein and as to be guided thereby, and a common driving mechanism disposed between the cross-head elements of said second pair for reciprocating said two pairs of cross-head elements in timed relation relative to said die-
15 supporting means.

FREDERICK K. MAUSSNEST.
